UNITED STATES PATENT OFFICE

2,210,010

MULTIPLE VACUUM TUBE

Walter Soller, Cincinnati, Ohio, assignor of one-half to William H. Woodin, Jr., Tucson, Ariz.

Original application January 31, 1935, Serial No. 4,393. Divided and this application February 2, 1939, Serial No. 254,301

6 Claims. (Cl. 250—27.5)

My invention relates broadly to electron tube devices and more particularly to a multiple electrode structure in an electron tube for multiple circuit operation.

5 This application is a division of my copending application Serial Number 4,393, filed January 31, 1935, for Television system; and the electron tube herein described is intended principally for use as an amplifier of the plurality of simultaneously transmitted video signal currents in television systems of my invention, such as described in the aforesaid copending application.

10 One of the objects of my invention is to provide a multiple electron tube of unitary construction for independently conducting separate components of a complex signal.

15 Another object of my invention is to provide a construction of multiple element electron tube for the separate amplification of the modulated currents of different frequencies in a television receiver adapted for the simultaneous use thereof.

20 A further object of my invention is to provide a construction of multiple electron tube having a common cathode electrode and a plurality of independent control grid and anode combinations associated therewith for separate operation in respect to individual signal components.

25 Still another object of my invention is to provide electronic shielding means intermediate different control grid and anode electrodes in a multiple electron tube structure, whereby separate electron streams from different portions of a common cathode extending through all of the compartments formed by the shielding means 30 may be independently controlled by said control grids and received at the respective anode electrodes.

35 A still further object of my invention is to provide a construction of screen grid for a multiple compartment electron tube of the type above described, with the screen grid substantially coextensive with the cathode and likewise common to the different control grid and anode electrodes.

40 Another object of my invention is to provide a construction of screen grid electrode as described and wherein the screen grid is cooperatively related to the structural as well as the electrical characteristics of the electron tube so that the tube structure is made compact, rigid, and substantially uniform and dependable in performance.

45 Other and further objects reside in the constructional and electrical features of the multiple electron tube of my invention hereinafter de-

scribed in more detail with reference to the accompanying drawings in which:

Figure 1 is a vertical sectional view through a multiple unit, multiple electrode electron tube of my invention taken substantially on line 1—1 in Fig. 2; Fig. 2 is a horizontal cross-sectional view of the electron tube shown in Fig. 1; Fig. 3 is a partial vertical sectional view on an enlarged scale, taken on line 3—3 in Fig. 2; Fig. 4 is a cross-sectional view showing a modified construction; Fig. 5 is a perspective view of the elements of the multiple electron tube of my invention in disassembled relation; and Figs. 6, 7 and 8 are schematic diagrams showing a number of modified forms of television receiving systems embodying the multiple electron tube of my invention.

50 While the electron tube of my invention is disclosed in application to the amplification of the separate currents in television systems of my invention, its use is clearly not limited thereto. In television systems of this type, however, the tube has a special advantage in that the plurality of currents as delivered from the frequency separating apparatus need not be of the magnitude required for operating the picture producing means, as amplification is readily provided in the multiple electron tube of my invention herein described.

55 Referring to the drawings in more detail, Fig. 1 shows the multiple electron tube of my invention in two vertical sectional portions, the upper substantially a cross section diametrically of the tube, and the lower a section within the glass envelope 16 showing the screen grid in elevation.

60 A common cathode electrode, 15, is supported centrally of the glass envelope 16. A heater element, 18, is disposed within the cathode. A multiplicity of control grid and anode electrodes, designated generally by reference characters 19 and 20, respectively is provided. Between each set of control grid and anode electrodes is provided a separator partition consisting of two discs of mica, designated by 21, and an intermediate disc 22 of metal. The metal disc is provided with a larger aperture 22a in the center than are the two mica discs, the apertures 21a in which are substantially the diameter of the cathode 15. The mica discs are adapted to be spaced along the length of the cathode electrode, and the metal disc, by virtue of its larger aperture, can be supported between the mica discs insulated from the cathode. The metal discs 22 are provided as equi-potential surfaces to serve as shields between the

compartments. A common screen grid electrode 83 is provided of such shape that it envelopes the anode electrodes. A slot 83a in the outer surface of the screen grid permits connections to be made 5 to the anode electrodes 80. Horizontally disposed slots 83b are provided in the screen grid electrode 83 to permit the insertion of the mica and metal separator partitions. A space 84 is provided, where the screen grid bends back to envelop the 10 anodes, for the entrance of the connections to the control grids.

Fig. 2 is a cross-sectional view of the tube shown in Fig. 1 and shows the glass press forms which seal the connections to the several anode and 15 control grid elements.

Fig. 3 is an enlarged vertical sectional view on an axis displaced 90° with respect to the axis of the vertical section shown in Fig. 1. Fig. 3 illustrates particularly the disposition of the elements 20 in the sections of the multisection amplifier tube 76, showing the heater 78, the cathode 75, the control grid 79, the anode 80, and the screen grid 83 in assembled relation; and showing also the mica discs 81 and the metal disc 82 arranged as 25 a shielding partition between the sections, the mica discs being disposed on either side of the metal disc and insulating it from the electrodes. The manner in which the partitions are supported in the slots 83b in the screen grid 83 is ap- 30 parent from Fig. 3.

Fig. 4 is a cross-sectional view showing a modified form of the electron tube of my invention. Means are shown in Fig. 4 whereby the connections to the several grid electrodes are brought 35 out in a staggered arrangement thereby lessening interterminal capacity effects.

Fig. 5 is a perspective view of the elements of the electron tube of Fig. 1 shown in disassembled relation. The simplicity of the component parts 40 is evident from this illustration thereof separately. It is intended that the parts be assembled in the most convenient and efficient manner, with but one specific requirement, that is, that the cathode be inserted through the apertures 45 in laminations 81, 82, and through grids 79 after all these elements are in proper relation in conjunction with screen grid 83 and the anode electrodes 80. The inherent stiffness of the assembly due to the structure of the screen grid and separator laminations is preserved by the sealing of 50 the rod supports of the various electrodes in the glass envelope 76.

The control grid electrode 79 is preferably cylindrical in form as shown, but may be provided in an open sided form for insertion after the cathode is mounted in the apertures of the separator laminations 81, 82. The other elements also may be of modified form, within the scope of 55 my invention, while preserving the particular 60 features and operational characteristics of my invention.

Fig. 6 is a schematic diagram showing one arrangement of apparatus in a television receiving system of my invention, of the type shown in my 65 application Serial Number 4,393, supra. Condenser 111, connected to the output circuit of the conventional television receiver, offers a high impedance to currents of scanning frequency but a low impedance to currents of light modulated 70 carrier frequency while the choke coil 117 offers low impedance to currents of scanning frequency and high impedance to the light modulated carrier frequency currents. The output of the condenser branch of this filter circuit is connected, 75 in this arrangement, to vibrating reed frequency

separator units 118, of a type shown in my co-pending application Serial Number 4,393, supra, wherein the several frequency components of the picture current are separated. The output of the vibrating reed units is connected through the 5 multiple electron tube hereinbefore described and schematically shown at 124 in Fig. 6 to the picture producing apparatus here designated by reference character 119, which is of a type shown in my application Serial Number 4,393, supra. The 10 scanning component of the current is conducted through an amplifying tube 120, to an oscillating coil in the picture producing apparatus. Means for adjusting the amplitude and the synchronism of this current are provided at 121 and 123, re- 15 spectively.

Fig. 7 shows a receiving system similar to that of Fig. 6 but employing vibrating wire frequency separator apparatus at 128 of the type shown in my copending application Serial Number 4,393, 20 supra, instead of the vibrating reed apparatus at 118 in Fig. 6. The arrangements of Figs. 5 and 6 are otherwise similar. The use of the electronic vibrating wire apparatus 128 to supply the input voltages for the tube 124 requires an additional 25 source of power for the anodes thereof. Source 135 is local to the vibrating wire apparatus, providing simply bias potential. The voltage of source 136 is divided by resistors 137, 138, 139 and 140, that across resistor 137 supplying anode potential 30 to the electronic vibrating wire apparatus 128, through resistors 141 which provide the control voltages applied to the individual control grids of the multiple amplifier tube 124. The potential drop across resistor 138 supplies bias potential for the control grids of tube 124; and that across resistor 139, the bias potential for the screen grid. The voltage across resistors 139 and 140 determines the potential of the anodes of tube 124 with 35 respect to the cathode, the same being applied 40 through the light units of the picture apparatus 119. Resistors 138, 139, 140 are the equivalent of the battery sources shown connected with the tube 124 in Fig. 6, as is more apparent with reference to Fig. 8 wherein the same vibrating reed 45 frequency separator units 118 are employed for energizing the control grids of tube 124; the potential drop across resistor 138 supplies the bias 50 potential for the control grids of tube 124, Fig. 8, the same being applied through the separate coils of the vibrating reed units 118.

The potential drop across resistor 139, Fig. 8, supplies screen grid bias, as in Fig. 7, and together with the voltage across resistor 140 supplies operating potential to the anodes. The electronic picture apparatus 125, Fig. 8, is a picture tube of the type shown in my copending application Serial Number 733,300, filed June 30, 1934, renewed December 9, 1938, for Television system; and resistors 142 are provided in the anode circuits of the multiple amplifier tube 124 to provide operating potentials for the grid electrodes of the picture tube. Other operating voltages for the picture tube are derived from the source 136 by 60 additional resistors, as indicated.

Thus, while I have described my invention in certain preferred embodiments and applied, by way of example, to different circuit arrangements, I desire it understood that modifications may be made in the structure and adaptation of 70 the device within the scope of my invention, and that no limitations upon my invention are intended except as are imposed by the scope of the appended claims.

What I claim as new and desire to secure by 75

Letters Patent of the United States is as follows:

1. Means for individually amplifying each of a plurality of currents comprising a multiple section electron tube, said tube including a common cathode electrode, a heater element for said cathode electrode, a common screen grid electrode, a plurality of control grid electrodes, a corresponding plurality of anode electrodes, and a plurality of partitions each comprising a pair of mica discs and a metal disc mounted therebetween, said discs being apertured to pass the common cathode electrode therethrough, the aperture in said metal disc being larger than the apertures in said mica discs, said screen grid electrode being slotted to accommodate said partitions, one of said anode electrodes and one of said control grid electrodes supported in each of the sections formed by said partitions, terminal supports connected with each of said anode and control grid electrodes, said screen grid being arranged to envelop said anode electrodes and being provided with passageways allowing the entrance of said terminal supports, and an evacuated glass envelope enclosing the above mentioned elements of said tube and providing supporting means therefor. 5
2. An electron tube comprising an elongated envelope, a plurality of anode electrodes supported from one side wall of said envelope, a corresponding plurality of control grid electrodes supported from the opposite side wall of said envelope, with said grid and anode electrodes substantially coaxial and operatively arranged in pairs, a cathode electrode common to all said pairs of grid and anode electrodes and extending coaxially therewith, insulated shield means arranged normal to said cathode and disposed intermediate the several pairs of grid and anode electrodes, and means for supporting said shield means. 10
3. A multiple electron tube comprising a single cathode electrode, corresponding pluralities of anode and control grid electrodes operatively arranged in pairs with respect to said cathode, and a screen grid electrode of double wall formation and substantially cylindrical in form, and having a longitudinal opening to the space between the double walls thereof and a longitudinal passage into the space within the inner wall thereof, means extending through said opening for supporting said anode electrodes in the space between the walls of said screen grid, and means extending through said passage for supporting said control grid electrodes. 15
4. A multiple electron tube comprising single cathode and screen grid electrodes, and corresponding pluralities of control grid and anode electrodes, with partition shield means disposed between cooperative pairs of anode and grid electrodes, and said screen grid constructed to support said means in position. 20
5. A multiple electron tube comprising single cathode and screen grid electrodes, corresponding pluralities of control grid and anode electrodes cooperative in pairs with respect to said cathode and screen grid electrodes, and dual insulating laminations and an intermediate conductive lamination constituting a partition shield member disposed between each pair of said control grid and anode electrodes, said screen grid having transverse slots therein adapted to receive and support said partition shield member. 25
6. A multiple electron tube comprising a substantially cylindrical envelope, a pencil-like cathode electrode mounted centrally of said envelope; a double walled substantially cylindrical screen grid electrode mounted coaxially of said envelope and having a longitudinal opening to the space between the double walls thereof and a longitudinal passage into the space within the inner wall thereof, said screen grid electrode having transverse slots therein; partition shield members comprising dual insulating laminations and an intermediate conductive lamination mounted in the slots in said screen grid electrode, said members being centrally apertured to pass said cathode electrode in insulated relation; a plurality of substantially cylindrical unitary control grid electrodes mounted coaxial with said cathode intermediate said partition members, each 30 said control grid electrode having a supporting rod connector attached thereto extending through the passage in said screen grid electrode and through said envelope in insulated relation; and a corresponding plurality of arcuate shaped unitary anode electrodes mounted coaxial with said control grid electrodes intermediate said partition members and between the double walls of said screen grid electrode, each said anode electrode having a supporting rod connector attached thereto extending through the opening in said screen grid electrode and through said envelope in insulated relation; and means for making electrical connection with said cathode and screen grid electrodes. 35
7. A multiple electron tube comprising a substantially cylindrical envelope, a pencil-like cathode electrode mounted centrally of said envelope; a double walled substantially cylindrical screen grid electrode mounted coaxially of said envelope and having a longitudinal opening to the space between the double walls thereof and a longitudinal passage into the space within the inner wall thereof, said screen grid electrode having transverse slots therein; partition shield members comprising dual insulating laminations and an intermediate conductive lamination mounted in the slots in said screen grid electrode, said members being centrally apertured to pass said cathode electrode in insulated relation; a plurality of substantially cylindrical unitary control grid electrodes mounted coaxial with said cathode intermediate said partition members, each 40 said control grid electrode having a supporting rod connector attached thereto extending through the passage in said screen grid electrode and through said envelope in insulated relation; and a corresponding plurality of arcuate shaped unitary anode electrodes mounted coaxial with said control grid electrodes intermediate said partition members and between the double walls of said screen grid electrode, each said anode electrode having a supporting rod connector attached thereto extending through the opening in said screen grid electrode and through said envelope in insulated relation; and means for making electrical connection with said cathode and screen grid electrodes. 45
8. A multiple electron tube comprising a substantially cylindrical envelope, a pencil-like cathode electrode mounted centrally of said envelope; a double walled substantially cylindrical screen grid electrode mounted coaxially of said envelope and having a longitudinal opening to the space between the double walls thereof and a longitudinal passage into the space within the inner wall thereof, said screen grid electrode having transverse slots therein; partition shield members comprising dual insulating laminations and an intermediate conductive lamination mounted in the slots in said screen grid electrode, said members being centrally apertured to pass said cathode electrode in insulated relation; a plurality of substantially cylindrical unitary control grid electrodes mounted coaxial with said cathode intermediate said partition members, each 50 said control grid electrode having a supporting rod connector attached thereto extending through the passage in said screen grid electrode and through said envelope in insulated relation; and means for making electrical connection with said cathode and screen grid electrodes. 55

WALTER SOLLER.
